UNITED STATES PATENT OFFICE.

LAWRENCE Y. SPEAR AND HUGO E. GRIESHABER, OF NEW LONDON, CONNECTICUT.

CONSTRUCTION AND CONNING EQUIPMENT FOR SUBMERSIBLE BOATS.

1,072,392.

Specification of Letters Patent.

Patented Sept. 2, 1913.

Application filed July 27, 1911. Serial No. 640,772.

To all whom it may concern:

Be it known that we, LAWRENCE Y. SPEAR and HUGO E. GRIESHABER, both citizens of the United States, residing at New London, 5 county of New London, State of Connecticut, have invented certain new and useful Improvements in Construction and Conning Equipment for Submersible Boats; and we do hereby declare the following to be a full, 10 clear, and exact description of the invention, such as will enable others skilled in the art to which it appertains to make and use the same.

The invention relates to the construction 15 and arrangement of the upper midship section and the navigating equipment of a submersible vessel, such as a submersible torpedo boat.

In a companion application, Serial No. 20 642,487, filed August 5, 1911, we have disclosed a submarine vessel having at the midship section an upstanding housing having a flat top of considerable extent which 25 serves as a navigating bridge, the housing being so shaped as to constitute a fair-water, and inclosing an observation tower, periscope tubes, and ventilators, as well as a hatch trunk extending from the main hatch to the bridge. The submersible boat 30 disclosed in that application has a navigating station on the bridge for use when the vessel is running on the surface, and a second navigating station, equipped with a navigator's periscope, within the hull of the 35 vessel, and an observation tower serving primarily as a trimming station.

The present application relates to a submersible vessel preferably having substantially the same upstanding housing and elevated navigating bridge, but it has a conning tower large enough to accommodate two or more men, and constituting a navigation station when submerged. This conning tower is equipped with a navigator's 40 periscope, speaking tubes, and other adjuncts necessary for the navigation of the vessel, including a steering station, and engine room telegraph and torpedo firing devices if desired.

50 The invention further contemplates improvements in structural details, which will be fully understood from a consideration of the following description of a preferred embodiment of the invention.

55 In the drawings, Figure 1 is a vertical central longitudinal section of the upper

midship portion of the boat; Fig. 2 is a section on the line 2—2 of Fig. 1; Fig. 3 is a section on the line 3—3 of Fig. 1; and Fig. 4 is a plan view of the parts shown in Figs. 60 1 and 2.

As is customary in vessels of this type, the vessel shown has a strong hull A constructed to withstand the pressure of deep submergence, which has a superstructure B 65 running the length thereof with a flat top constituting the main deck of the vessel. Built into the strong hull and constituting an upward projection therefrom, and itself so constructed as to withstand the pressure 70 of deep submergence, is the conning tower C, which constitutes a navigating station when submerged, and may be equipped with torpedo firing devices, and is of sufficient capacity to accommodate at least two men. 75 This conning tower has at the base a contracted opening into the interior of the vessel, which opening is provided with a water-excluding closure e; whereby it may, if desired, be shut off from the interior of the 80 vessel. Rising from the top of the conning tower, at one end thereof, is an observation hood d containing observation port-holes, through which one of the officers in the conning tower may make observations. This 85 hood is particularly useful in the operation of trimming the vessel. The hood also constitutes a cover for the conning tower hatch, and for that purpose is provided with a hinge connection to the top of the tower, 90 and with mechanism for locking it in the closed water excluding position, as shown in Fig. 1. Directly beneath the hood are arranged two platforms e e' at different levels, these platforms being hinged to the 95 side of the tower so that they may be thrown up or down. The upper one, e, serves for the officer to stand on when he is using the observation hood, and the other, e' when he is assisting as second officer in the navigation 100 of the vessel submerged. At the other end of the tower is arranged the navigator's periscope D, and beneath it a platform h upon which the navigating officer using the periscope stands. The tower is also preferably provided with observation port-holes h' 105 at a convenient level for use by an officer standing on either the platform h or the platform e', and it is also equipped with navigating adjuncts including compass t, 110 and speaking tubes s, or telephones, not shown.

The vessel is provided with an additional periscope E which extends down to a station within the hull, which may be equipped with steering gear, torpedo firing control 5 and other adjuncts as is the case with the conning tower station, either station being available at the option of the commanding officer. This additional periscope is arranged at the extreme after portion of the 10 conning tower, preferably outside of the strong wall thereof, as shown in Fig. 1, and between the two periscopes E and D is arranged a ventilator F, having at the top a hinged flat cover f, to the underside of 15 which is fastened an operating cord as shown, and also having, at the bottom, the emergency closure f', which serves as an additional security against the admission of the water of the sea, in case the upper portion 20 of the ventilator is punctured or otherwise caused to leak. In the preferred construction the two periscopes, with their surrounding housings, and the ventilator, are built into a single inclosing structure J tapered at its ends to constitute a fairwater. 25

The conning tower, in the preferred construction is surrounded by an upstanding housing G, of considerable extent, shaped to constitute a fairwater, and of which the flat 30 top forms a navigating bridge. This housing is open to the sea, and is self-bailing and self-filling, and it is partitioned off just aft of the conning tower to constitute a hatch trunk H extending from the main 35 hatch to the bridge, the said trunk having a hinged cover m at the top, and the hatch having a cover n equipped with mechanism for locking it in a closed position. This arrangement of fairwater and hatch trunk 40 is, however, disclosed and claimed in our co-pending application referred to, and constitute no part of the present invention. On the said bridge is installed a standard O carrying an electrical controller for steering 45 mechanism, and preferably also an engine room telegraph, so that the vessel may be navigated from this bridge. Within the housing are also included the forward and aft ventilators N and M, and these ventilators 50 should be equipped with water-excluding valves as is the ventilator F.

It will be understood from the foregoing description that when the vessel is running on the surface it may be navigated from 55 the elevated navigating bridge; which it is to be submerged, the observation hood d may be used during the trimming operation; and after submergence the vessel is

navigated either from within the conning tower, or from the station in the hull. In 60 either case one periscope is available for lookout or supplementary purposes in preferred form of the invention and the after periscope is made the higher of the two, so that, if the commanding officer desires to 65 take station in the body of the boat instead of in the conning tower, he may do so as a view directly ahead is obtained with both periscopes and either one may be used for steering on a range when submerged or for 70 laying the boat upon a target.

What we claim is:

1. A conning tower for submersible vessels having at one end a periscope and at the other end an observation hood, a platform beneath the periscope, and two platforms arranged one above the other beneath the observation hood, the upper platform being so supported that it may be moved from above the lower platform and 80 being at such a level that a man standing on it can make observations through the observation hood. 90

2. In a submersible vessel, a conning tower having a periscope at one end thereof, 85 an additional periscope extending down within the hull of the vessel at the same end of the conning tower, and a fairwater on top of the conning tower about the two periscopes. 90

3. In a submersible vessel, the combination with a hull and conning tower thereon of a periscope tube leading from said hull, a second periscope tube leading from said conning tower and a casing inclosing and combined with said periscope tubes to form a single projecting structure above 95 said conning tower. 100

4. In a submersible vessel, the combination with a hull and a conning tower thereon of a periscope tube leading from said hull, a second periscope tube leading from said conning tower, a ventilator leading from said conning tower and a casing inclosing and combined with said periscope tubes 105 and said ventilator to form a single projecting structure above said conning tower.

In testimony whereof we affix our signatures, in presence of two witnesses.

LAWRENCE Y. SPEAR.
HUGO E. GRIESHABER.
